DESIGN FOR A SHAMPOO REST

Addie Hayes Roberts, Atlanta, Ga.

Application October 17, 1947, Serial No. 141,961

Term of patent 3½ years

(Cl. D86—10)

To all whom it may concern:

Be it known that I, Addie Hayes Roberts, a citizen of the United States, residing at Atlanta, in the county of De Kalb, and State of Georgia, have invented a new, original, and ornamental Design for Shampoo Rest, of which the following is a specification, reference being had to the accompanying drawing, forming part thereof, and wherein:

Fig. 1 is a plan view of the shampoo rest.

Fig. 2 is a front view.

Fig. 3 is a side view.

Fig. 4 is a cross section taken along the line 4—4 of Fig. 2.

Fig. 5 is a cross section taken along the line 5—5 of Fig. 1.

I claim:

The ornamental design for a shampoo rest, substantially as shown.

ADDIE HAYES ROBERTS.
